IGNITION APPARATUS

Raymond Edgar White, Sidney, N. Y., assignor to
Bendix Aviation Corporation, New York, N. Y.,
a corporation of Delaware

Original application March 7, 1947, Serial No.
733,233. Divided and this application Decem-
ber 29, 1948, Serial No. 67,791

3 Claims. (Cl. 171—209)

1

This invention relates to electrical apparatus and more particularly to current generating and distributing devices adapted for use in ignition systems of internal combustion engines or the like and is a division of my co-pending application Serial No. 733,233 filed March 7, 1947.

One of the objects of the present invention is to provide novel apparatus of the above type which is specially adapted for but not limited to use in a high frequency condenser discharge ignition system.

Another object of the invention is to provide novel apparatus for generating electrical energy in a manner readily adapted for use in ignition systems of modern aircraft engines having large numbers of cylinders.

Still another object is to provide novel apparatus for distributing electrical energy in a predetermined manner to a plurality of loads of points of use.

A further object is to provide novel current distributing means which is so constructed as to be compact without introducing danger of flashovers and pre-ignition.

A still further object is to provide novel means in an ignition unit of the above type wherein the electrical wiring is simplified and wherein electronic units are novelly mounted for mechanical support and electrical connection.

Another object is to provide a novelly constructed magnetogenerator wherein a permanent magnet is so installed as to facilitate recharging thereof.

The above and further objects and novel features of the invention will more fully appear from the following detailed description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a vertical sectional view with parts broken away illustrating one form of current generating and distributing apparatus embodying the present invention;

Fig. 2 is a diagrammatic illustration of the magnetic circuit of the current generating means of Fig. 1;

Fig. 3 is a front elevation of a casting which may be employed in the construction of the distributor block;

2

Fig. 4 is a sectional view taken substantially on line 4—4 of Fig. 3;

Fig. 5 is a front elevation illustrating the completed distributor block and showing the relative positions of the brushes of the distributor rotor;

Fig. 6 is a sectional view taken substantially on line 6—6 of Fig. 5, and showing the distributor rotor in dotted lines;

10 Fig. 7 is an elevation view, on a reduced scale, of a mounting and wiring plate with the cover removed;

15 Fig. 8 is a diagrammatic view looking from the right in Fig. 1 and schematically indicating the electrical circuit; and

Fig. 9 is a detail view, partly in section, illustrating the mounting and electrical connections for an electronic tube.

One embodiment of the invention is illustrated in the drawings, by way of example, in the form of a unit comprising a relatively low voltage magnetogenerator, an ignition distributor and timing control elements electrically and mechanically associated with each other in

20 a novel manner, said control elements comprising electronic means novelly mounted in the unit. The supporting structure of said unit includes a frame member 10 (partly broken away) adapted to be secured to an engine casing, or the like, in any known manner, and a member 11, the two members being secured together by a plurality of stud bolts 12. A shaft 13 is rotatably supported by bearings 14 and 15 in the frame members and is adapted to be rotatably driven by the engine through a splined sleeve 16.

25 The novel magnetogenerator comprehended by the inventions is adapted, in spite of its small size, to generate a relatively large number of current alternations or surges during each revolution of shaft 13. The particular structure illustrated produces 14 flux reversals through the coil per revolution of the shaft, and, when the latter is driven at one-half engine speed, sufficient current impulses are generated to supply ignition for a 14 cylinder four cycle engine. The

30 40 45 50 55 flux divider or rotor 17 comprises two laminated sleeves or rings 18 and 19 axially spaced on shaft 13 by non-magnetic means and suitably secured against axial and angular movement relative to the shaft. The periphery of each of said flux conducting rings is formed to provide seven radial projections or poles (Fig. 2) and the poles of one ring alternate circumferentially with the poles of the other. A larger or smaller number of such projections may be provided, depending

on the particular use to which the unit is to be put.

Below rotor 17 there is mounted in frame member 10 a pair of stationary, preferably laminated, pole shoes 22 and 23, the upper concave surfaces of which are in flux conducting proximity to and have the same curvature as the outer surfaces of rings 18 and 19, respectively. A bar magnet 24 is mounted between the free ends of stator pole shoes 22 and 23 so that one shoe contacts the north pole of the magnet and the other shoe contacts the south pole. With the magnet mounted in this novel manner a coil of wire may be wound around it for the purpose of remagnetizing the same or remagnetizing may be effected by contacting the poles 22, 23 with the poles of another magnet.

Mounted above the rotor 17 is a transformer coil 25 having a primary winding P and secondary windings 69 (Fig. 8) wound on a laminated core 26 which is secured to frame member 10 by studs 27 with the ends thereof in magnetic contact with the upper ends of a pair of pole shoes 23 and 29. The latter are fixedly mounted in frame member 16 in any suitable manner known to the art and each extends into magnetic flux conducting relation with both rings 18 and 19 of rotor 17. When the rotor is in a position such that pole 23 is adjacent a projection on sleeve 18, the pole 29 is opposite a projection on sleeve 19. Upon rotation of the rotor through one-fourteenth of a revolution from that position, pole shoe 29 will cooperate with ring 19 and pole 23 will cooperate with ring 18. Thus, with the rotor in any one of seven equally spaced positions, the magnetic lines of flux flow from the north pole of magnet 24 through stator pole 23, rotor sleeve 18, pole shoe 29 and back to the south pole of the magnet through core 26, pole shoe 28, rotor sleeve 18 and stator pole 22. With the rotor in any of seven other or intermediate positions, the lines of magnetic flux flow in the opposite direction through the coil, that is, from the north pole of the magnet through stator pole 23, sleeve 18, pole shoe 28, core 26, pole shoe 29, rotor sleeve 18 and stator shoe 22. Pole shoes 28 and 29 are preferably divided into two or more branches adjacent the rotor in order to cooperate with more than one projection on each of the flux conducting sleeves 18 and 19. However, one shoe on each of these poles may be sufficient. If desired, the second set of said pole shoes may be connected with the core of another coil and thus provide a dual magneto.

In a manner well understood in the art, the magnetic lines of flux, thus caused to flow through coil 25, effect the flow of electrical current in the primary winding P of the coil. The circuit which includes said primary winding comprises a circuit breaker 30 (Fig. 8) operated by a rotatable cam 31 for periodically opening said circuit in accordance with known practices. The opening of the primary circuit at opportune moments causes a sudden collapse of the magnetic field around coil 25 and hence the induction of current flow at a higher voltage in a secondary winding of the coil which is connected in an ignition circuit in a manner to be more fully herein-after described.

Novel current distributing means are provided in combination with the above described energy generating means for distributing the electrical energy induced in the secondary winding of coil 25 to spark plugs in a plurality of engine cylinders, said distributing means being novelly so

constructed and connected with the source of energy that a large number of spark plugs firing in rapid succession may be supplied through a relatively small distributor without material danger of undesirable flashovers which tend to occur particularly at high altitudes and cause preignition in the cylinders. In the form shown, the distributor means comprises a stationary insulating block 32 surrounding shaft 13 and a finger or rotor 33 of insulating material mounted on shaft 13 for rotation therewith.

The construction of distributor block 32 is best illustrated in Figs. 5 and 6 as comprising a molded insulating block 34 having three concentric rings of arcuate contacts 35, 36 and 37 projecting from one face thereof. The total number of contacts in the two inner rings (14 are shown but more or less may be provided) represents the number of spark plugs or other such loads served by the distributor, and each of these contacts 35 and 36 is provided with a terminal boss 38 and 39, respectively, which extends through block 34 for connection with an outgoing cable 40. In the present embodiment, the outer ring consists of seven live segments 27 which alternate with seven longer segments 41 which are not in any electrical circuit but serve to mechanically bridge the live segments. Contact segments 37 are all electrically connected together by a wire ring 42 or the like, which is embedded in block 34 and has electrical contact with projections 43 on segments 27. At least one of the latter has a terminal boss 44 (Fig. 3) by which ring 42 may be connected to the source of energy.

In the construction of the distributor block, a metal casting illustrated in Figs. 3 and 4 is first prepared and the ring 42 is placed thereon. The casting comprises a flat disc-like annular portion 45 with the terminal bosses 38, 39, 44 and projections 43 extending in an axial direction therefrom. The disc is radially slotted at equal intervals, such as at 46, and has projections 47 thereon which serve to anchor segments 41 in the insulating block of the finished structure. The insulating material 34 is molded around the casting of Fig. 3 and the projecting face or disc portion 45 thereof is then cut along the circular grooves 48 to form three rings which are in turn cut along seven equally spaced radial grooves 49 to form the segments heretofore described. A sturdy and reliable structure embodying a large number of parts is thus simply and inexpensively constructed. Block 32 may be mounted in frame member 11 by means of a plurality of studs 50 which engage internally threaded inserts in the block.

The distributor rotor 33 comprises a block of insulating material molded around a sleeve 51 which is in turn keyed to shaft 13. A pair of carbon brushes 52, 53 slidably extend through passages in one end of rotor 33, the former being adapted to engage the outer ring of segments 37, 41, and the latter being adapted to engage the inner ring of segments 35. The free ends of said brushes have small coil springs 54 secured thereto and connected by a stiff conducting bridge 55, the center portion of which is connected to an extension spring 56 that is in turn suitably anchored in rotor 33. Thus, the brushes are resiliently held in engagement with their respective contact segments. A second pair of similarly mounted brushes 57 and 58 (the latter being shown diagrammatically only in Figs. 5 and 6) at the other end of rotor 33 serve to connect the

outer ring of contact segments 37 with the middle ring of segments 36.

The pairs of brushes 52, 53 and 57, 58 are so arranged as best seen from the dotted line positions indicated in Fig. 5, that whenever current flows to input terminal 44 only one of the two outermost brushes 52 and 57 is in contact with a live segment 37, the other being at that time in contact with a dead or disconnected segment 41. Current is thus supplied alternately through the two sets of brushes, and hence, alternately to the contacts in the two inner rings of segments 35 and 36. Preferably, only one of the two brushes 52 and 57 is in contact with a segment 37 at any given instant.

Novel means are also provided in combination with the above structure for simplifying the electrical wiring and mounting of the elements incorporated in the ignition system of which the magneto-distributor means described above are part. As illustrated, said means include a panel 60 of insulating material secured in position on the frame 13, 11 by any suitable means such as bolts 12. Said panel 60 comprises a base plate 61 (Fig. 7) and a cover 62 (Fig. 1) cemented thereon, the plate having recesses and grooves in the covered face thereof for receiving a plurality of contact elements 63 and connecting wires therefor, as best seen in Fig. 7. Panel 60 has a large opening 64 cut in the center thereof and the circuit breaker 30 and a contactor or circuit maker 65 are conveniently mounted on frame member 11 in said opening for operation by the fourteen lobe cam 31 which is mounted on the free end of shaft 13.

Mounted in a novel manner on the back of the upper left corner of panel 60, as viewed in Fig. 8, is a full wave rectifier 66 which has its input terminals 67 and 68 connected to opposite ends of the secondary winding 69 of coil 25, said winding being center tapped to ground at 70. The alternating current generated in secondary winding 69 is thus converted into a unidirectional current at the output or plate terminal 71 of the rectifier. The latter preferably comprises a hollow metallic envelope 72 in which the operative elements are mounted. Suitable leads, such as lead 73, from said element extend through a seal in the bottom of the envelope in accordance with known practice.

In order to simplify the electrical connections to the rectifier tube 66 and to provide a suitable mounting therefore, said tube is secured to a recessed block 74 of insulating material by means of an internally flanged sleeve 75 that engages the shoulder 76 on said block and a flange 77 on the tube. A wavy spring washer 78 is preferably interposed between flange 77 and block 74. Molded into the closed end of the block is a terminal insert 79 for each electrical connection to the tube. Each of said inserts has an opening in which a lead or terminal wire, such as 73, is soldered or otherwise suitably secured, and a threaded opening for receiving a combined terminal and mounting stud 67. The studs 67 extend through panel 60 and serve as electrical terminals, as well as mechanical means for securing the tube and its mounting on panel 60. When a connection internally of the panel is to be made, terminal stud 67 is electrically connected with an element 63 through a lock washer 80. If, an external connection is to be made, the end of the external cable is merely connected with the head of stud 67 or other similar stud in any well

known manner, such as in the manner illustrated at 81. (Fig. 1.)

In the embodiment illustrated, output terminal 71 of the rectifier tube is internally connected through a lead 82 to one side of a storage condenser 83, the other side of which is grounded at 84. Condenser 83 is installed in a cylindrical casing which is held firmly in position by a bracket member 85 that is integral with frame member 11 and forms a cradle therewith for receiving the condenser casing. The terminal of the condenser extends through an opening 86 in panel 60 into which extends the tongue of an element 63 mounted in the panel.

15 The output terminal 71 of the rectifier is also connected through an internal lead 87 to the anode terminal 88 of a gaseous discharge tube or electronic valve 89 which may be mounted on panel 60 in the same manner as the rectifier. The 20 grid terminal 90 of the discharge tube is connected by an external lead 91 to one contact 111 of contactor 65 and by an internal lead 92 to a terminal 93 of a special unit 94 which may be conveniently called RCL unit. The latter includes 25 a grid stabilizing resistor 95 between terminals 93 and 96, a grid charging resistor 97 and a grid condenser 98 in series between terminals 96 and 99, a grid current limiting resistor 100 in series with resistor 97 between terminals 99 and 101, 30 and a reactance coil 102 between terminals 96 and 103, the latter terminals being externally connected to ground through a conducting strip 104 and a mounting bolt 12. Terminal 99 is connected by internal leads 102 and 105 to the output 35 terminal of the rectifier and terminal 101 is connected by an external lead 106 to the other contact of contactor 65. The remaining terminal 103 of unit 94 is internally connected by lead 107 to the cathode terminal 108 of the electronic valve 40 89 which latter terminal is in turn connected by an external lead 109 to the input contact segments 37 of the distributor heretofore described.

The circuit breaker 30 may be constructed in accordance with the disclosure of Shoemaker et al., Patent No. 1,866,492. When the spring mounted follower 110 rides up on a lobe of cam 31, it is effective to lift the upper spring mounted contact of the breaker away from the lower fixedly mounted contact and thereby break the primary 50 circuit of the magneto. Contactor 65 is similarly constructed, except that the fixed contact is replaced by a spring mounted contact 111, the outward (downward, as viewed in Fig. 8) movement of which is limited by a stop 112 and the inward 55 (upward) movement is yieldably resisted by a spring 113. Thus, when the spring mounted follower 114 is on a lobe of the cam, the contacts are separated. As the follower rides down into a valley of the cam, the contacts engage thereby 60 closing the circuit and causing the spring or flexible arm on which contact 111 is mounted to move away from stop 112. Since the contacts are then free to move as a unit, any danger of one bouncing relative to the other at high operating speeds is 65 virtually eliminated.

In operation, each time the points or contacts of circuit breaker 30 are operated by cam 31 which is driven at one-half engine speed with shaft 13, a surge of current is induced in one of the secondary windings 69 and passes through rectifier 66 to uni-directionally charge condensers 83 and 98, the flow of current to the latter being restricted by resistor 97. At this time the electronic valve 89 is non-conductive. Thereafter, when 75 it is desired to fire one of the spark plugs 115, the

cam permits the points or contacts of contactor 65 to close thereby permitting condenser 98 to discharge through the grid circuit of the electronic valve 89 and thereby render the latter conductive to the charge on storage condenser 83. The latter accordingly discharges across the anode and cathode of tube 89 through the distributor in the manner heretofore fully described and thence through the primary winding 116 of a transformer coil, the secondary winding 117 of which is connected in series with the spark plug 115. The reactance coil 102 is provided for preventing damage to discharge tube 89 in the event of a short in the output circuit thereof.

There is thus provided a novelly constructed, compact unit for generating and distributing high frequency current impulses at timed intervals to a plurality of spark plugs in the cylinders of an internal combustion engine. Said unit is a novel combination embodying novel generating means, novel current distributing means and novel simplified means for mounting and connecting the more or less fragile electronic tubes and other elements which may form a part of a high frequency ignition system.

Although only a single embodiment of the invention has been illustrated and described in detail in the drawings and the foregoing specification, it is to be expressly understood that the invention is not limited thereto. For example, if it is desired to do so, the contactor 65 may be placed in circuit between the storage condenser 83 and the input terminal 44 of the distributor, thereby eliminating discharge tube 89 and the RCL unit 94. Other types of rectifiers, such as selenium rectifiers may be used. Various other changes could also be made, particularly in the specific construction, design, and arrangement of parts illustrated, without departing from the spirit and scope of the invention, as will now be readily apparent to those skilled in the art. For a definition of the limits of the invention, reference is had primarily to the appended claims.

What I claim is:

1. In a magnetogenerator, a rotor comprising two axially spaced annular flux conducting members each having an equal number of radially extending projections equally spaced about the periphery thereof and the projections of one member being arranged alternately with the projections of the other member, a stator pole shoe arranged in flux conducting relation with each of said members, a magnet disposed between and in contact with said pole shoes and such that the lines of magnetic flux flow through the magnet in a direction longitudinally of the axis of rotation of said members, two pole shoes each bridging the space between and being associated with both of said members in flux conducting relation, said last named pole shoes being arranged to alternately cooperate with said members and in a manner such that when one is in flux conducting relation with one member during rotation of the rotor, the other is in flux conducting relation with the other member, and a coil inductively associated with said last named pole shoes.

2. In a magnetogenerator, a rotor comprising two axially spaced annular flux conducting members each having an equal number of radially extending projections equally spaced about the periphery thereof and the projections of one member being angularly displaced with respect to and arranged alternately with the projections of the other member, a stator pole shoe arranged in flux conducting relation with each of said members, a permanent magnet disposed between and in contact with said pole shoes and such that the lines of magnetic flux flow through the magnet in a direction longitudinally of the axis of rotation of said members, two pole shoes each of which bridges the axial space between and is associated with both of said members in flux conducting relation, said last named pole shoes being arranged to alternately cooperate with said members and in a manner such that when one is in flux conducting relation with one member during rotation of the rotor, the other is in flux conducting relation with the other member, each of said last named pole shoes having portions adapted to cooperate simultaneously with at least two projections on each said member, and a coil inductively associated with said last named pole shoes.

3. A magnetogenerator comprising a rotatably mounted flux divider consisting of axially spaced flux conducting rings, each of said rings having an equal number of equally spaced radially extending projections and the projections of one ring alternating circumferentially with the projections of the other ring, a stationary bar magnet, a pole shoe extending from one end of said magnet into permanent flux conducting relation with one of said rings, a pole shoe extending from the other end of said magnet into permanent flux conducting relation with the other of said rings, a coil having a core, pole shoes extending from opposite ends of said core into flux conducting relation with said rings, the free ends of said last named pole shoes being arranged so that each of said shoes bridges the axial space between said rings and alternately cooperates with each of said rings as the latter rotate and so that when one of said last-named pole shoes is in flux conducting relation with one of said rings the other of said last-named pole shoes is in flux conducting relation with the other of said rings.
